[57] CLAIM

The ornamental design for an indirect lighting fixture, substantially as shown and described.

DESCRIPTION

FIG. 1 is a perspective view of an indirect lighting fixture of my design showing the bottom and side thereof;

FIG. 2 is a perspective view of the indirect lighting fixture of FIG. 1, showing the top and side thereof; FIG. 3 is a side, elevational view of the indirect lighting fixture of FIGS. 1 and 2;

FIG. 4 is a top, plan view of the indirect lighting fixture of FIG. 3; and

FIG. 5 is a bottom, plan view of the indirect lighting fixture of FIG. 3.

FIG. 1**FIG. 2****FIG. 3****FIG. 4****FIG. 5**
